UNITED STATES PATENT OFFICE

2,499,446

DIRECTION FINDER

Benjamin F. Anthony, Kirkwood, Mo.

Application March 19, 1946, Serial No. 655,497

2 Claims. (Cl. 230—249.5)

1

This invention relates to new and useful improvements and structural refinements in direction finders, and the principal object of the invention is to provide a device of the character herein described, which is adapted for use with ventilating fans and the like, for the purpose of determining the direction of air current produced by the same.

Generally speaking, the invention consists of a source of light positioned substantially at the center of the fan, the light rays emanating from said source and the air current produced by the fan being coordinated toward a common focus, whereby the direction of the air current may be readily and conveniently determined as aforesaid.

A further object of the invention is to provide a direction finder which does not, in any way, interfere with the normal operation of such fan and in which the light source may be turned off if desired, as soon as the direction of the air current has been determined.

Another object of the invention is to provide a direction finder whereby the fan may be adjusted before being set in motion, thus eliminating the conventionally experienced hazard of sustaining injury to one's fingers, while attempting to adjust the fan in motion.

An additional object of the invention is to provide a direction finder which is applicable to both new fans and those already in use.

A still further object of the invention is to provide a direction finder which is of simple construction and which, in addition to its use with ventilating fans as above set forth, may be generally employed in association with blowers of all descriptions, hair dryers, and the like.

With the above more important objects in view, and such other objects as may become apparent as this specification proceeds, the invention consists essentially of the arrangement and construction of parts as illustrated in the accompanying drawings, in which:

Figure 1 is a side elevation of a ventilating fan showing the invention thereon.

Figure 2 is a front view of the same.

Figure 3 is a cross-sectional view, taken in the plane of the line 3—3 of Figure 2 and illustrating the invention per se.

Figure 4 is a side elevation showing the invention as used on a blower, and

Figure 5 is a front elevation of the subject illustrated in Figure 4.

Like characters of reference are used to design-

2
nate like parts in the specification and throughout the several views.

Referring now to the accompanying drawings in detail, the invention consists of a light source designated generally by the reference character 10, the same comprising a lamp shell 11, configured substantially as shown.

A socket 12 is mounted upon the back wall 13 of the shell 11 by suitable bolts 14 and an incandescent lamp 15 is replaceably positioned in the socket. A suitable reflector 16 is mounted behind the lamp 15 and a lens 17 is positioned in the remaining end of the shell 11, as will be clearly apparent from the accompanying drawings.

The shell 11 is also provided with a suitable switch 18, the latter being in circuit with the lamp 15 by means of the conductor 19. A further conductor 20 connects the entire lamp assembly to a suitable source of current.

The shell 11 may be welded or otherwise similarly secured to the radially extending bars 21 of the guard 22, such as is usually associated with the ventilating fan 23. Alternatively, the shell may be provided with a suitable mounting flange (not shown), this in turn being adapted for connection to the fan guard.

It will be noted that the lamp assembly 10 is positioned substantially at the center of the fan and when the invention is placed in use, the light rays 24 emanating from the lamp are directed to coincide with the direction of air current 25 produced by the fan. In other words, the light rays and the air current are directed in a same general direction, whereby the direction of the air current may be readily and conveniently determined.

It is believed that the advantages resulting from the use of the invention will be readily understood from the foregoing disclosure, and further description thereof at this point is therefore considered unnecessary.

Referring now to the accompanying Figures 4 and 5, the same illustrate the invention as applied to a blower, designated generally by the reference character 26. Herein, the construction of the lamp assembly 10 is similar to that already described and it should be noted in this connection that the invention may be used with ventilating, air-blowing and similar other appliances in general, as well as in hair dryers and other like machines, wherever it is required to determine the direction of air current.

While in the foregoing there has been shown and described the preferred embodiment of this

invention it is to be understood that minor changes in the details of construction, combination and arrangement of parts may be resorted to without departing from the spirit and scope of the invention as claimed.

What I claim as my invention is:

1. In association with a fan having a guard attached thereto, a source of light comprising an elongated lamp shell having a forward and rear end and a socket therein, for supporting an incandescent lamp, a reflector behind said lamp, a lens in front of said lamp attached to said shell, a switch in said shell and in circuit with said lamp, means associated with said shell and positioned between said switch and the rear end of said shell for attaching said shell to the fan guard.

2. An air flow direction finder comprising a fan having a guard associated therewith, a source of light comprising a lamp shell attached to the center of said guard and extending partially on each face of said guard, a socket in said shell, for supporting an incandescent lamp, a reflector be-

hind said lamp, a lens in front of said lamp, and a switch in said shell and in circuit with said lamp, the light rays emanating from said lamp and the air flow produced by said fan being coordinated toward a common direction for the purpose of determining the direction of the flow of air.
